DRIVE FOR RECORDING AND REPRODUC-
ING DEVICES

Arno Rysick, Dresden, Germany

Application March 7, 1935, Serial No. 9,811. Re-
newed May 20, 1937. In Germany March 2,
1934

7 Claims. (Cl. 74—190)

This invention relates to driving means for the turntable of plate or disc recording and/or reproducing devices.

One object of the invention resides in the provision of new and improved means of the character described, which shall be economical of manufacture, compact; and effective to drive the turntable of a dictating or like machine at any one of a plurality of different speeds.

Yet another object of the invention consists in the provision of driving means of the character described, which may be readily manipulated to produce a wide range of operating speeds of the turntable from a single constant speed of the driving means, the speeds of the turntable being arranged to be accelerated or decelerated in minute or relatively great increments.

Other objects and advantages will be apparent in the following description of a preferred embodiment of the invention which has been selected for illustration in the accompanying drawings. It will be understood however that many changes in form, construction and arrangement, may be made by those skilled in the art, without departing from the scope and spirit of the invention as expressed in the appended claims.

In the accompanying drawings:

Figure 1 is a plan view of a driving means embodying a preferred form of the invention, the turntable being partially broken away to better illustrate the driving means.

Fig. 2, a similar view as that shown in Fig. 1, but with the driving members differently adjusted;

Fig. 3, a side view of the driving members; and Fig. 4, a view of the drive in disengaged position.

A prime mover, preferably an electric motor (not shown) is arranged to drive a shaft 1, the upper end of which is provided with a plurality of stepped driving cones 2. The depending flange 3 of the turntable journaled on a vertical axis A is shown in vertical elevation in Fig. 3 and in plane cross-sectional views in each of Figs. 1, 2 and 4. It will be understood that the disc-supporting surface of the turntable is coincident with the plane defined by the upper edge of the flange 3, as shown in Fig. 3.

To the frame 4, shown in Fig. 3, of the motor, not shown, a plate 5 is secured forming the carrier for the entire switching arrangement. This base plate 5 carries a set screw 7 on which another plate 6 is guided by means of the slot 8. The plate 6 further possesses a lengthening piece 9 which at its front end carries a roll 10 and is

also embraced by a bow 11 disposed on the plate 5. The plate 5 has also a projection 12 similar to the projection 13 arranged on the opposite end of the plate 6. Between the two projections 12, 13 a tension spring 14 is fixed which has the tendency to draw the displaceable plate 6 into its highest end position.

The plate 6 constitutes the engageable and disengageable carrier for the transmission gears and for this purpose is provided with a bearing bolt 10 15 which, directly above the plate 6, supports a friction disc 16 connected with a superposed friction disc 17 of smaller diameter. Above the friction disc 17 the journal or bolt 15 carries an elbow lever 18 provided at its angular end with 15 a journal or bearing pin 19 for a third friction disc 20 of medium diameter and articulated at its free end to a control lever 23 by means of the hinge pin 21 and the drawbar 22. The control lever 23 is arranged on a pivot 24 which is 20 disposed outside the range of the turntable in the frame of the device. In Fig. 1 one end position of the control lever 23 is shown at which the friction disc 20 engages directly between the friction disc 2 arranged on the motor shaft 1 and 25 the driving edge 3 of the turntable. As indicated in the drawings, at this position, the other friction discs 16, 17 will not contact with the driving edge 3 or the friction disc 2 on the motor shaft 1. In Fig. 2, the other end position of the 30 control lever 23 is shown, at which the friction disc 20 arranged on the bell crank 18 is indicated only by dots and dashes to improve the view. At this position of the parts, the plate 6 has been farther drawn up by the spring 14. The bell 35 crank 18 has been swung about the pin 15 to render motion of the carrier 6 impossible. The parts are then in the position at which the largest friction disc 16 engages the driving wheel 2 whereas the friction disc 17 firmly connected with 40 the friction disc 16 hugs the edge 3 of the turntable. Transmission is effected from the motor shaft to the driving edge 3 of the turntable by means of the wheels 2, 16, 17.

At the position of parts according to Fig. 1 the 45 turntable will have a speed of approximately 78 revolutions, which corresponds to gramophone speed, so that discs on which sound has been recorded at this speed by a suitable device can be instantly reproduced by a gramophone.

At the position of parts according to Fig. 2 the turntable has a slower speed amounting approximately to only 33 revolutions and being suited only for dictating machines for taking as much dictation as possible on each plate. Slight regu- 55

lations of the speed are possible by axially displacing on the motor shaft the driving wheel 2 formed as a cone. The engagement of the friction wheels will always be maintained, as the spring 14 takes care that the friction discs are properly pressed in between the motor shaft and the driving edge.

The switching device is used also as starting and stopping device for the machine by having 10 a control lever 26 movably arranged on a pin 25 in the machine frame. The control lever 26 is positioned with its front end in a guide 27 which fixes the end positions of the control lever 26. On another pin 28 arranged in the machine 15 frame an adjusting lever 29 is provided which with its front sloping end is placed on the guide roll 10 disposed on the plate 6. The lever 29 is articulated to the control lever 26 by means of a drawbar 30. The control lever 26 projects 20 from the casing of the device and can be brought into one or the other end position. At the position of the control lever 26 shown in Figs. 1 and 2 the adjusting lever 29 is so high up that the friction wheels are in engagement with the edge 25 of the turntable and the motor shaft, so that transmission of motion from the driving motor to the turntable is possible. On the other hand, if the control lever 26 is brought into the position according to Fig. 4, the adjusting lever 29 30 will be moved so as to press with its front end upon the guide roll 10 and thus push the carrier 6 for the friction wheels 16, 17, 20 into lowermost position to bring it out of engagement with the turntable as well as with the friction 35 cone 2 on the motor shaft 1. Transmission of motion is thereby interrupted and the turntable stopped. It is immaterial whether the control lever 23 is in the position according to Fig. 1 or 2, that is, whether the one group of friction 40 wheels is in operative position or the other friction disc. Starting and stopping by means of the lever 26 is possible without any trouble, as all the control parts are articulated to one another and capable of cooperating in any motion.

45 The invention is not limited to the embodiment shown, but may be carried out in other ways. For example, the displaceable carrier could carry several sets of friction wheels which alternatively become operative, so that the turntable can rotate at more than two speeds.

50 I claim:

55 1. A drive for a recording and reproducing device for plates or discs, comprising a casing, a turntable in said casing, a driving edge on the circumference of the turntable, a driving motor in said casing, a movable carrier displaceably disposed on said casing, a bearing pin on said carrier, a lever pivoted on said bearing pin, a pair of friction wheels journaled on said bearing pin 60 and a friction wheel journaled on said movable lever, said carrier being movable into and out of position to establish a driving connection from said motor through said pair of wheels to the driving edge of said turntable, said lever being effective to move the wheel thereon into and out of position to establish a driving connection from said motor to the said edge of the turntable.

65 2. In a drive of the character described, the combination of a prime mover, a rotatably supported disc having a depending flange, a carrier member slidably mounted in underlying relation with respect to said disc, a lever journaled on said carrier, a friction wheel on said carrier coaxial with said lever and adapted to engage said 70 prime mover, a second friction wheel coaxial

with, and arranged to be rotated by, said first mentioned wheel and to drivingly engage the flange on said disc, a friction wheel journaled on said lever eccentrically of the lever axis and adapted to simultaneously engage both the prime mover and disc flange in one position of said lever, means to actuate said lever, and means to actuate said carrier.

3. In a drive of the character described, the combination of a prime mover, a rotatably supported disc, a carrier member slidably mounted in underlying relation with respect to said disc and in close proximity thereto, a plurality of friction wheels journaled on a fixed axis on said member for joint rotation in planes parallel to the plane of said disc and intermediate the disc and carrier member, a lever pivoted on said friction wheel axis, a friction wheel journaled on said lever for rotation in a plane parallel to the plane of said disc, a depending flange on said disc, means to move said carrier member into and out of position to cause said plurality of wheels to provide a driving engagement between said prime mover and the flange on said disc, and means to move said lever to cause the wheel thereon to form a driving engagement between said prime mover and said flange when said carrier is out of position with respect to said plurality of wheels.

4. In a drive of the character described, the combination of a prime mover, a rotatably supported disc, a carrier member slidably mounted with respect to said disc and in close proximity thereto, a plurality of friction wheels journaled on a fixed axis on said member for joint rotation in planes parallel to the plane of said disc, a lever pivoted on said carrier, a friction wheel journaled on said lever for rotation in a plane parallel to the plane of said disc, a flange on said disc, means to move said carrier member into and out of position to cause said plurality of wheels to provide a driving engagement between said prime mover and the flange on said disc, and means to move said lever to cause the wheel thereon to form a driving engagement between said prime mover and said flange in one position of said carrier.

5. In a drive of the character described, the combination of a prime mover, rotatably supported disc, a flange on said disc, a carrier member slidably mounted with respect to said disc and in close proximity thereto, a plurality of friction wheels journaled on a fixed axis on said member for joint rotation in planes parallel to the plane of said disc, yieldable means tending to slide said carrier member in a direction to provide a driving connection between said plurality of wheels, said prime mover and the flange on said disc, a lever pivoted on said carrier, a friction wheel journaled on said lever for rotation in a plane parallel to the plane of said disc, means to move said carrier in a direction reverse to that in which the carrier is moved by said yieldable means to disengage the driving connection between said prime mover and said disc and means to rotate said lever to form a driving connection between said prime mover, the wheels on said lever and said disc.

6. In a drive of the character described, the combination of a prime mover, a rotatably supported disc, a carrier member slidably between two positions, a plurality of friction wheels journaled on a fixed axis on said member for joint rotation in planes parallel to the plane of said disc, a flange on said disc, a lever pivoted on said

carrier, a friction wheel journalled on said lever for rotation in a plane parallel to the plane of said disc, means tending to move said carrier into one of its said positions to cause said plurality of wheels to provide a driving engagement between said prime mover and the flange on said disc, manual means to move said carrier to the second of the said positions to disable the driving connection between said prime mover, said plurality of wheels and said disc, and means to actuate said lever to cause the wheel thereon to form a driving engagement between said prime mover and said flange when said carrier occupies a position identified with the disabled condition of said plurality of wheels.

7. In a drive of the character described, the combination of a prime mover, a rotatably supported disc, a carrier member slidably supported with respect to said disc in close proximity thereto, said carrier member being movable between

two spaced positions, yieldable means tending to move said carrier to one of said positions, a plurality of friction wheels journalled on said member and operable in the position to which said yieldable means tends to move said member to provide a driving connection between said prime mover and said disc, a friction wheel movably supported on said carrier member for rotation on an axis extending parallel to the rotary axes of said plurality of friction wheels, means to move said carrier to the second of its positions in which said plurality of wheels are disabled from driving connection between said prime mover and said disc, and means to move said last mentioned friction wheel bodily when said carrier occupies said last mentioned position to provide a driving connection between said prime mover, said last mentioned friction wheel and said disc. 15
